UNITED STATES PATENT OFFICE.

DANIEL W. THOMAS, OF RICHMOND, INDIANA.

PLOW.

Application filed April 30, 1926. Serial No. 105,820.

This invention relates to a plowshare, one of the objects being to provide a device of this character the point and shearing portions of which can be made separate from the share so that it is thus possible to form the body portion or blade of cast metal while the point and the shearing edge can be made of a better grade of material such as a steel forging or a high grade malleable casting.

Another object is to provide simple and efficient means whereby the separate parts of the device can be firmly attached to each other, it being possible readily to disconnect a broken part and replace it with a new one without discarding the entire plowshare.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,
30 Figure 1 is a top plan view of a portion of a plowshare embodying the present improvements.

Figure 2 is a bottom plan view of the structure shown in Figure 1.

35 Figure 3 is a section on line 3—3, Figure 2.
Figure 4 is a section on line 4—4, Figure 1.

Figure 5 is a section on line 5—5, Figure 1.
Figure 6 is a top plan view of a portion of a modified form of plowshare.

40 Figure 7 is a section on line 7—7, Figure 6.

Referring to the figures by characters of reference 1 designates the blade of the plowshare provided with a blunt nose 2 from the inner side of which is extended a tongue 3 constituting an extension of a side flange 4 formed beneath one side of the blade. This blade, with its integral tongue can be made of any suitable material such as cast iron, and, in the structure illustrated in Figures 1 to 5 inclusive a recess 5 is provided in the upper surface of the blade extending from the forward end or nose as shown.

Arranged in front of the nose of the blade 1 is a point 6 having an integral shearing wing 7 extending obliquely therefrom at such an angle that when the back end of the

point is seated against the nose 2 the wing 7 will extend under the adjacent side portion of the blade 1 as shown in Figure 4 and will project laterally beyond the blade to 60 provide a shearing edge 8. The wing 7 can be recessed as illustrated at 9 to receive the adjacent edge portion of the blade 1 and a desired number of ears 10 can be extended laterally from this recessed portion for the 65 reception of bolts 11 the heads of which are countersunk into the blade 1.

Formed in that side of the point remote from the wing 7 is a longitudinal recess 12 for the reception of the tongue 3, the end of 70 this recess being preferably shaped to provide a recess or pocket 13 to receive the pointed end 14 of the tongue 3. A longitudinal groove 15 is formed in the top face of the point 6 and is adapted to register 75 with the recess 5. The forward end portion of this groove is widened as shown at 16 so as to extend to one side of the point and this wide portion of the groove is deeper than the remaining portion as shown at 17, thereby 80 providing a transverse shoulder 18.

The point 6 has a web 19 integral therewith and extending under the nose or forward portion of blade 1. A wear plate 20 is fitted snugly in the groove 15 and has a 85 thickened portion 21 seated within the deepest portion 16 of the groove. This thickened portion provides a transverse shoulder 22 designed to bear against the shoulder 18. Plate 20 is of sufficient length to extend into 90 the recess 5 where it is fastened by a bolt 23 extending through the plate 20, nose 2 and web 19. As plate 20 is held in the groove 15 by rivets 24 or the like it will be apparent that the parts will thus be held together securely. Plate 20 can be of a good 95 grade of steel and its forward end may, if desired, extend slightly beyond the front end of the point 6 so as to receive most of the wear. Should this plate become worn to 100 an objectionable extent it could be removed from the point and another plate substituted. Should the point 6 or its wing 7 become broken or worn another one can be used in lieu thereof.

If desired, and as shown in Figures 6 and 7, the use of a separate connecting plate 20 can be dispensed with. In this modified structure the point 24 and its wing 25 have a web 26 integral therewith for extending 110 under the share 27. A recess 28 can be provided in the top surface of the blade of the

share to receive a tongue 29 integral with the point. Thus when a bolt 30 is extended through the tongue, blade and web the parts will be held together securely as shown in Figure 7.

What is claimed is:

1. In a plowshare a blade having a blunt forward end and a recess in the top face of said end, a point abutting against said end, 10 a wing extending therefrom under and laterally beyond one side edge of the blade, there being a groove in the top face of the point provided with a transverse shoulder, a wear plate seated within the groove and 15 engaging the shoulder, one end of said plate being seated within the recess in the blade, means extending through the plate and blade for fastening them together, and means for securing the plate to the point.
- 20 2. A plowshare including a blade having a blunt end provided with a recess in its upper face, a tongue integral with and extending forwardly from one side of said blunt end, a point for abutment against said end, said 25 point having a recess in one side terminating in a pocket for the reception of the tongue, a wing extending from the point along one side of the blade, a web connecting the point and wing and extending under the blade, a

member projecting from the point and seated in the recess in the blade, and means extending through said member, blade and web for holding the point to the blade. 30

3. A plowshare including a blade having a blunt end provided with a recess in its upper face, a tongue integral with and extending forwardly from one side of said blunt end, a point for abutment against said end, said point having a recess in one side terminating in a pocket for the reception of the tongue, a wing extending from the point along one side of the blade, a web connecting the point and wing and extending under the blade, a member projecting from the point and seated in the recess in the blade, and means extending through said member, blade and web for holding the point to the blade, 35 said means including a plate seated within and flush with the top surface of the point, one end of said plate projecting forwardly beyond the point, and cooperating shoulders carried by the plate and point for transmitting thrust from the plate to the point. 40

In testimony that I claim the foregoing as 55 my own, I have hereto affixed my signature.

DANIEL W. THOMAS.
